2 Sheets-Sheet 2

A technical drawing of a belt with a central oval hole and a rectangular buckle. The belt has a textured surface. To the left of the belt, the numbers 20, 21, 22, 23, 24, 25, 26, and 27 are arranged vertically, likely indicating sizes. To the right of the belt, the numbers 21, 22, 23, 24, and 25 are arranged vertically.

UNITED STATES PATENT OFFICE

JAMES MELCHOR HOFFER, OF STEELTON, PENNSYLVANIA, ASSIGNOR TO BETHLEHEM STEEL COMPANY, A CORPORATION OF PENNSYLVANIA

SWITCH HEATER

Application filed January 12, 1931. Serial No. 508,101.

This invention relates to improvements in heating devices and has particular reference to a means for heating railway switches.

The primary object of the invention is the provision of a simple, inexpensive and effective device of the class described which will thoroughly heat the switch points to prevent the accumulation of snow and ice thereon.

Another object of the invention resides in the provision of a cover, having novel features of purpose and design, for the burner.

The novel features will be more fully understood from the following description and claims taken with the drawings.

Fig. 1 is a plan view of part of a railway switch showing the heaters in position therewith;

Fig. 2 is a view taken on the line 2—2 of Fig. 1;

Fig. 3 is a plan view of the heater;

Fig. 4 is an elevation of the heater partly in section;

Fig. 5 shows an end view of the heater; and,

Figs. 6 and 7 are plan and elevation views respectively, of the cover for the burner.

Referring to the drawings, 10 designates the track rails, 11 the movable switch rails, and 12 the cross-ties supporting the rails.

The heater consists of a rectangular box-like structure 13 which forms the compartment for the supply of a liquid fuel such as oil. At one end of the box is located a burner tube 14 which projects through an opening in the top of the box and extends downwardly

to the bottom of the fuel compartment. This tube is rectangular in section, the bottom end being slotted to establish communication between the fuel compartment and the wick 15, which substantially fills the tube. The wick

may be composed of any suitable non-combustible absorbent, such as mineral wool, asbestos fibre, or the like, so as to conduct the oil to the burning end of the wick by capillary attraction. The burner tube is welded to the

box at the junction of the opening through the top of the box and the walls of the tube.

A sliding cover 16 is provided for the upper end of the burner, to protect the wick from the weather when not in use and for the additional purpose of regulating the flame ac-

cording to its position over the burner. The cover is formed from a flat plate, flanged along its longitudinal edges so as to overlap the burner tube. The flanges are made deeper at the rear end of the cover to form heels 55 17, which are adapted to ride on the top of the box, while the under side of the cover rests upon the burner tube and flush therewith as shown in Fig. 4. The cover is provided with a slot 18, through which projects 60 a bolt 19, secured to the box, to limit the movement of the cover. A wing nut 20 is employed to clamp the cover in any desired position relative to the burner. It will be noted that the heel 17 is at all times to the 65 rear of the bolt 19 when the cover is in position on the heater, and when the nut 20 is tightened, the front end of the cover is pressed tightly against the top of the burner tube. The bolt is welded to the box so as to seal the 70 hole through which it passes and to hold it in position. At the front end of the cover, a portion 21 is cut away to conform with the inside opening of the burner tube. This leaves projecting portions 22, adapted to remain in contact with the top and sides of the burner when the cover is in its fully retracted position without blanking any portion of the burner. The slot in the cover being located 75 so that the cover cannot be moved backwardly beyond this position. The upturned portion 23 provides a handle for the cover.

The filling spout 24 is provided with a hinged cover 25 which is adapted to prevent water from entering the box. The hinge bracket 26 is formed with stops 27 which prevent the cover from being opened beyond a predetermined position so that the cover will close automatically of its own weight, when released.

To the sides of the box, adjacent the burner, are attached blinds 28, for the purpose of keeping the burner in spaced relation to the base of the rail and to prevent the flame from coming into contact with the cross ties when the heater is positioned under the rails and between the ties.

A handle 29 is welded to the rear end of the heater for convenience in handling.

In operation this invention provides a

heating device particularly adapted for heating railway-switches in cold weather. The heater may be positioned between two switch ties as shown in Figs. 1 and 2. The burner 14 is adjusted under the switch rails, with the blinds 28 touching the bottoms of the rails. A number of the heaters may be utilized throughout the length of the switch system, as disclosed in the drawings.

10 When the heater is not in use, the cover 16 is moved forward, covering the burner, and clamped in place by means of the wing nut 20. When snow or sleet occurs, the nut is released and the cover moved back to the extent 15 of the slot 18, or to any position within the length of the slot, and again secured by the nut. Thus, by being able to clamp the cover at any position, the area of the burner exposed for combustion may be positively fixed, and without tendency of the cover being displaced by the vibration of the car wheels 20 passing over the rails. The feature of the clamped cover also prevents dirt and water from fouling the burner when not in use, as 25 the cover may be held in positive and tight contact with the top of edges of burner. Any water accumulating on the top of the heater cannot enter the heater through the burner tube, as it projects above the top of the box.

30 Under certain weather conditions it may not be necessary to use the full area of the burner, therefore, being able to secure the cover in any position over the burner, economy is effected in the consumption of fuel.

35 While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

40 Having thus described my invention what 45 I claim as new and desire to secure by Letters Patent is:

1. A switch heater comprising a fuel receptacle, a burner projecting above the top of the receptacle, a cover slidably mounted over the burner, said cover being supported at one end by the burner, and at its other end by the top portion of the receptacle, means to limit the sliding movement of the cover, and means for clamping the cover to the burner.

55 2. A switch heater comprising a fuel receptacle, a burner tube projecting above the top of the receptacle, a cover slidably mounted over the burner, means to transversely retain the cover in position on the burner, said cover being supported at one end by the burner, and at its other end by the top portion of the receptacle, means to limit the sliding movement of the cover, and means for clamping the cover to the burner and to the receptacle.

3. A switch heater comprising a fuel receptacle, a burner tube projecting above the top of said receptacle and extending to the bottom thereof, an absorbent material in said tube, a slidable cover for the projecting end of said tube, said cover being supported at its forward end by said tube, the top portion of the receptacle forming a support for the rear end of the cover which is provided with downwardly projecting sides adapted to rest 70 on the top of the receptacle, means to limit the sliding movement of the cover, and clamping means for the cover.

4. A switch heater comprising a fuel receptacle, a burner tube projecting above the top of said receptacle and extending to the bottom thereof, an absorbent material in said tube, a slidable cover for the projecting end of said tube, said cover being flanged along its longitudinal edges so as to overlap said tube and to form a heel at the rear end of the cover adapted to rest upon the top of the receptacle for the purpose of maintaining the cover in horizontal alignment with the top of the burner, means to limit the sliding movement of the cover, and clamping means for the cover.

5. A switch heater comprising a fuel receptacle, a burner tube projecting above the top of said receptacle and extending to the bottom thereof, an absorbent material in said tube, a slidable cover for the projecting end of said tube, said cover being flanged along its longitudinal edges so as to overlap said tube, the flanges at the rear end of the cover being of greater depth than at the front end, a slot through the top of the cover and intermediate its ends, a bolt secured to the top of said receptacle and adapted to extend upwardly through said slot, and a nut for the bolt.

6. A cover for a switch heater formed with a burner, said cover comprising an elongated channel section having a top web portion and depending side flanges of greater depth at the rear end of the cover than at the front end, a slot through the web portion of said section, the rear end of said slot being positioned forward of the point of greatest depth of said flanges, the front end of said web portion being formed with a recess to conform with the inside opening of the burner, and a handle for the cover.

In testimony whereof I hereunto affix my signature.

JAMES MELCHOR HOFFER.
